UNITED STATES PATENT OFFICE.

CRESCENZO CAPUANO, OF LOS ANGELES, CALIFORNIA.

PANTS AND POCKET RULER.

Application filed March 22, 1926. Serial No. 96,559.

My invention is a pants and pocket ruler intended especially for measuring and marking the lining for pants and for outlining and marking the pockets.

An object of my invention is a ruler having curves and straight lines on the periphery together with straight and diagonal lines with rule markings on the interior portions, there being cut-out sections so that the rule may be used as a template for drawing the proper curves and straight lines on material to be used for linings for trousers or the like and also to mark different measurements for cutting pockets.

Another object of my invention is to incorporate in a rule, curved surfaces which may be utilized as stencils to make the flap for different types of pockets.

Another feature of my invention is forming the interior of the rule with lines meeting at an angle, such lines having measurements marked thereon, the measurements being intended to start from the intersection of lines ruled by using the edges of the rule, said lines intersecting at a different position than the intersection of the ruler edges themselves.

My ruler is formed with a straight edge on one end, a side edge having a gradual convex curve, an opposite side edge having a convex curve of sharper curvature than the side opposite, the curve merging into a curve at the opposite end from the end having the straight edge. The ruler thus formed may be utilized as a template for marking material to be used as pants lining. Some of the sides are provided with measuring markings and others with indications to show where notches or sections are to be cut in the material.

The inside portion of the ruler is formed with curved and straight edges, there being cut-out portions to facilitate the markings of side, top and inclined pockets and also having measurements to facilitate marking of hip and watch pockets or the like.

My invention will be more readily understood from the following description and drawings, in which;

Figure 1 illustrates my rule being applied to a trouser material to mark the side pockets.

Fig. 2 is a view of the application of my rule to trouser material for marking top or inclined top pockets.

Fig. 3 is a face view of one side of the rule.

Fig. 4 is a scale similar to that upon which the measurements of Fig. 3 are marked.

My rule will first be described by having reference to Fig. 3. The straight edge is designated by the numeral 1. A slightly curved side 2 has a slightly convex edge. The opposite side 3 is formed convex of much greater curvature than the side 2 and merges into the end 4. The corner 5 is an acute angle, the corner 6 an obtuse angle and the corner 7 substantially a right angle. A section 8 is removed out of the block of wood or the like to be used for making the rule and has a curved edge 9 following substantially the outer curved edges 3 and 4 for part of the length and has a straight diagonal edge 10. These edges meet at the corners 11 and 12.

A second cut-out section 13 has a slightly curved edge 14 substantially parallel to the curved edge 2; a reverse curve 15 forming a template for a watch pocket flap; a section 16 parallel to the curve 2; a straight edge 17 formed substantially at right angles to the curve 2 and a curve 18. These curves have the main corners 19, 20, 21, 22 and 23.

A third cut-out section 24 has opposite parallel edges 25 and 26; these being substantially parallel to the edge 17 and the cross edge 27 substantially at right angles to the sides 25 and 26. A reverse curve 28 forms a template for use in marking a hip pocked flap where a large flap is desired. There are short substantially straight edges 29 and 30 adjacent the reverse curve. The corners of this cut-out section are designated by the numerals 31, 32, 33, 34, 35 and 36.

A small cut-out section 37 has parallel side edges 38 and 39 contained substantially in alinement with the edges 25 and 26 and has also a cross edge 40 substantially parallel to the edge 27 with a reverse curve 41 considerably flatter than the curve 28. This forms a stencil for pocket flaps. The cut-out section 37 has sharp corners 42 and 43 and curved corners 44 and 45.

The measurements marked on the rule are substantially as follows:

The edge 2 has measuring marks 50 starting from the corner 5 and is indicated as measuring up to 4 in. A second measurement 51 starts from the 1 in. mark of the measurement 50 and is shown as marked 110

to 3 in. A third measurement 52 starts from the $1\frac{1}{2}$ in. of the 50 measurement and is shown with numerals 4 to 9 indicating 4 to 9 in. starting $1\frac{1}{2}$ in. from the corner 5.

8 The edges 25 and 38, and 26 and 39 have similar measurements 53 and 54; these having the zero at the edge 2 with the 1 in. mark therefor set in from the edge on the lines 25 and 26. It will be noted that these 10 measurements extend up to 6 in.

15 The edge 3 has measurements 55 which have the zero places substantially $1\frac{1}{4}$ in. from the corner 6 and extending around the edge; the measurement being shown as continuing to 7 in. It will be noted that the zero mark is substantially at right angles to the curve 3 and that the other marks up to 7 in. are made parallel to the zero mark.

20 The curved edge 9 has a measurement 56 shown as from 1 to 4 in. with the zero set inwardly from the corner 11. The side 10 has measurements 57 shown from 1 to 7 in. with the zero set inwardly from the corner 11. The object of this feature is so that 25 when a tailor is marking on the material to be cut with chalk the chalk mark will necessarily be somewhat set inwardly from the edges 9 and 10 and the intersection of the lines will form a corner and be the zero for 30 both of the scales 56 and 57.

35 The rule has various markings or indications thereon to show where cuts or slits or slight folds are to be made in the material marked. In the edge 3 two side marks 58 and 59, joined by a back line 60, indicate that in the trouser lining material slits are to be formed at the points 58 and 59 substantially the depth shown and a chalk mark drawn on the line 60 substantially parallel 40 to the edge 3. Two check marks 61 and 62 from the edge 3 adjacent the corner 6 are to be utilized in either making clippings with the scissors in the material marked or to make chalk marks.

45 It will be noted that there is a line 63 drawn parallel to the edge 3 from the corner 6 slightly inset from the edge. This line indicates the exact line on which the sewing or seam may be formed.

50 There are marking lines 64 and 65 extending from adjacent the corner 7 across the rule and terminating at the points indicated by the numerals 66 and 67 on the edge 1. These lines form the center lines on which the template is placed when the edges 3 and 4 are utilized for marking the lining material. The rule is preferably formed with similar markings on opposite sides so that it may be reversed and when so reversed the other side 55 may be readily marked by utilizing the same center line from the corner 7 to the points 66 or 67.

60 There is also an inset line 68 from the edge 1 having the same purpose as the inset line 63. Inset lines 69 are also formed par-

allel to the edge 18 continuing as a line 70 parallel to the edge 27. The line 71 is also parallel to the edge 40 and lines 72 and 73 parallel to the edges 25 and 38, and 26 and 39. The line 70 is continued forming a cross 70 measuring line 74. Pocket flaps are also provided with inset lines 75 to indicate the position of the binding seam.

It is not believed necessary to indicate all the uses to which my rule may be put in 75 forming linings for trousers or in being used as a template for pockets or the like. However, it may be stated that using part of the template formed by the curves 3 and 4 with the curve 2, the outline may be 80 drawn for forming the inside side pocket trousers. The cut-out section 24 may be utilized to measure hip pockets and for extra deep pockets the cut-out section 37 would be included.

85 The use of the reverse curves 15, 28 and 41 will be obvious as forming the shape for pocket flaps. In Fig. 1, the use of the side 3 for measuring side pockets of trousers is illustrated. The edge 3 is placed along the 90 seam of the trouser material and from the corner 6 or the marks 61 or 62 or the zero 59 measurements may be marked off indicating the length of cut required for the side trouser 95 pockets.

100 In Fig. 2 the use of the cut-out space 8 is indicated for marking inclined top pockets for trousers. In this case the scales 56 and 57 are utilized and a line drawn along the edge 10. Substantially every part of the rule, especially the parts marked by scales may be utilized in forming linings for trousers and in measuring the pockets. For convenience the scales 50, 51 and 52 do not read from the same point but from different positions along the edge 2.

105 It will be obvious that the scales and shape of cut-out sections as well as the general shape of the rule may be changed to adapt it for different purposes in tailoring or making clothes. Such changes however, will be within the spirit of my invention as set forth in the description, drawings and claims.

110 Having described my invention, what I claim is:

1. A rule having a body structure with a straight edge at one end, a convex curve at the other end, convex curved sides, the curve of one of the sides being merged into the curve at the end, said side having a sharper curve than the other side, the body structure having a plurality of cut-out sections, some of said sections having a reverse curve suitable to form a stencil to mark 120 pocket flaps.

2. A rule comprising a body structure having a straight edge at one end, opposite sides having convex edges, one being of greater radius than the other, the side of lesser radius having a curve merging into 130

- a convex curved end, the body structure having cut-out sections, some of said sections being formed with opposite parallel sides adapted to form markings for hip 5 pockets or the like.
3. A rule having a body structure with a straight edge at one end, a convex curved side of large radius having an acute angle with the end, the opposite side joining the 10 straight edge at an obtuse angle, said edge being convex and of lesser radius than the opposite edge, an end opposite the straight edge having a curve merged into the side edge of the lesser radius, said curved end 15 joining the side of greater radius at substantially right angles.
4. A rule having a body structure as claimed in claim 3, in which the body structure has a plurality of cut out sections, some 20 of said sections having edge lines substantially at right angles to the curved side of greater radius and having reverse curves adapted to mark pocket flaps.
5. A rule having a body structure as 25 claimed in claim 3, in which the body structure has two cut-out sections, said sections having side lines substantially at right angles to the edge having the greater curvature and both cut-out sections having a side 30 with a reverse curve adapted to mark pocket flaps.
6. A rule having a body structure with a straight edge at one end, a convex side of large radius, an opposite convex side of lesser radius, an end opposite the straight 35 edge formed convex, the said end and the side of lesser radius merging in a curve, the body structure having four cut-out sections, one section having a curve parallel to the merging curve of the end and side and 40 a diagonal line, two of the cut-out sections having side lines at substantially right angles to the side of greater radius, the fourth cut-out section having a curved edge, a straight edge at right angles to the side of greater radius, a reverse curve adapted to 45 mark a pocket flap and a curve parallel to the side of greater radius.
7. A rule having a body structure as claimed in claim 6, in which the two cut-out sections having sides at right angles to the side of greater radius have reverse curves adapted to mark pocket flaps.
8. In a rule having a body structure with a cut-out section, said section having a curve 55 on one side and a straight edge on the other, measurement markings on both said edges, said measurement markings commencing at a point set inwardly from a common joined corner of said edges to form a common zero 60 on an article being cut.

In testimony whereof I have signed my name to this specification.

CRESCENZO CAPUANO.
